ARTICLE ASSEMBLING APPARATUS

Edward Bertalan, Oak Park, Ill., assignor to
Western Electric Company, Incorporated, New
York, N. Y., a corporation of New York

Application July 11, 1946, Serial No. 682,809

9 Claims. (Cl. 29—203)

1

This invention relates to article assembling apparatus, and more particularly to apparatus for assembling plastic insulating discs in spaced relationship on a central conductor used in the manufacture of coaxial cables.

This application is a continuation-in-part of my copending application Serial No. 653,884, filed March 12, 1946, for "Assembling Apparatus."

Coaxial cables usually comprise a plurality of coaxial units assembled into a composite core which is thereafter covered with a metallic sheath. The coaxial units generally comprise a solid central conductor and an outer tubular conductor, which is held away from and maintained coaxially of the central conductor by means of wafer-like insulating discs uniformly spaced on the central conductor. One problem encountered in manufacturing this type of coaxial unit is the provision of suitable apparatus for applying the wafer-like insulating discs uniformly on the central conductor as it is advanced through a forming machine. In addition, the kind of material from which the insulating discs are made further complicates the development of suitable disc applying apparatus.

It has been suggested heretofore that insulating discs used in the manufacture of coaxial cable units be made of a suitable stiff material, such as hard rubber, or from a plastic, such as polystyrene. In the case of hard rubber it was found that centrally perforated, radially slotted discs could readily be punched from strips thereof and snapped on the central conductor quite successfully, whereas pre-slotted discs made from polystyrene could not be snapped on the central conductor without breaking the discs due to the brittle nature of the material. Because of the relatively poor electrical characteristics of hard rubber and the manufacturing difficulties involved in using polystyrene, the insulating discs generally used in the manufacture of coaxial cables are made of the plastic known as "polyethylene."

As its name implies, polyethylene is obtained by polymerizing ethylene. The usual commercial form of polyethylene is a moderately soft, pliable material having a high molecular weight and possessing excellent electrical insulating characteristics. Polyethylene is sufficiently hard to permit insulating discs made therefrom to maintain their shapes under ordinary circumstances, but it is soft enough to cause some manufacturing difficulties to arise when attempts were made to make slotted discs by punching them from strips thereof.

2

Furthermore, when slotted discs of the type formerly made of hard rubber were made of polyethylene and were forced upon a central conductor, the sides of the slots occasionally were deformed by the passage of the conductor therethrough. As a result, the discs would not adhere firmly to the central conductor and would tend to slide along the conductor or might even come off the conductor. In addition, it is relatively easy to force such pre-slotted discs off the conductor by a thrust applied on the sides of the discs opposite the slots and substantially longitudinally of the conductor, because the small amount of wall surface remaining in the central aperture of the radially slotted discs against which the conductor presses does not possess enough sheer strength to hold the discs in place. Consequently, coaxial cable units could not be satisfactorily manufactured by using discs made of polyethylene which had been pre-slotted and then forced on the central conductor.

In order to overcome these manufacturing difficulties, it was necessary to provide suitable means for cutting radial, line-like slits in annular polyethylene insulating discs, means for holding the slits open so that the central conductor may be passed therethrough into the central aperture without damaging the forward corners and sides of the slits, and means for applying the slotted discs to a central conductor with a wiping motion. It is evident that by cutting a line-like radial slit from the center aperture to the periphery of the disc, no material is removed from the disc. By virtue of this fact, the entire wall surface of the center aperture of the disc is preserved, and when such radially slit discs are in position on a central conductor, they will readily withstand considerable thrust applied on the sides of the discs adjacent to the slit. Furthermore, discs so applied to a central conductor adhere more forcibly thereto because the natural resiliency thereof causes the sides of the radial slit to close together, whereby the conductor is firmly gripped by the walls of the center aperture and is also engaged by a substantially solid ring of insulating material.

The present invention makes it entirely practical to use soft and pliable insulating discs in the manufacture of coaxial cable units by providing a coordinated apparatus for radially slitting the discs and thereafter applying them on a continuously moving conductor with a wiping motion in one operation.

An object of the invention is to provide new and improved article assembling apparatus.

In accordance with a preferred embodiment of the invention, as applied to the application of insulating discs on a continuously moving conductor of a coaxial unit, there is provided a reciprocating disc applying apparatus including a reciprocably mounted slide which is reciprocated parallel to and in timed relation with the continuously advancing conductor and substantially faster in a direction opposite to that in which the conductor is moving. A platen is movably positioned on the slide and has oscillatory means positioned thereon for receiving centrally perforated insulating discs, slitting the discs radially and simultaneously applying the discs in predetermined uniform spaced relation on the advancing conductor.

A clear understanding of the invention may be had from the following detailed description of a specific embodiment thereof, when read in conjunction with the appended drawings, in which:

Fig. 1 is a front view, on a reduced scale, of a reciprocating disc applying apparatus embodying the invention;

Fig. 2 is a longitudinal, vertical, sectional view taken along line 2—2 of Fig. 3, showing certain members at the beginning of their disc applying stroke;

Fig. 3 is a fragmentary, plan view of a portion of the apparatus shown in Fig. 2, showing the position of some of the parts at the beginning of a disc-applying stroke;

Fig. 4 is a vertical section, taken along line 4—4 of Fig. 3;

Fig. 5 is a plan view of the apparatus with parts broken away, showing the parts in their full operated position;

Fig. 6 is a side view of the apparatus showing certain members at the end of their disc applying stroke;

Fig. 7 is a fragmentary, plan view of a portion of the apparatus showing the position of a tripping means at the end of the disc-applying stroke;

Fig. 8 is an enlarged, fragmentary, plan view of a portion of the apparatus showing an oscillatory disc carrier and its associated disc slitting knife;

Fig. 9 is an enlarged, fragmentary, sectional view taken along line 9—9 of Fig. 8;

Fig. 10 is an enlarged, perspective view of a knife used for radially slitting the discs;

Fig. 11 is an enlarged, perspective view of a short length of a central conductor with slitted discs assembled thereon by means of the disc applying apparatus of this invention and showing an outer tubular conductor surrounding the discs;

Fig. 12 is an enlarged, fragmentary, sectional view taken along line 12—12 of Fig. 1;

Fig. 13 is an enlarged view of a typical hinged joint provided on articulated disc feed chutes forming a part of the apparatus;

Fig. 14 is a right hand vertical view of the hinged joint shown in Fig. 13;

Fig. 15 is a fragmentary, sectional view taken along line 15—15 of Fig. 2, and

Fig. 16 is a diagram showing how discs are placed upon a conductor by apparatus embodying the invention.

Referring to the drawings, particularly Fig. 1, there is shown a disc-applying apparatus, which is designed to assemble centrally perforated, annular, insulating discs 20—20 at predetermined, uniformly spaced intervals on a central conductor

10 21 being continuously advanced longitudinally above the disc-applying apparatus. The conductor 21 is advanced at a constant rate of speed in the direction of the arrows (Figs. 1, 2 and 3) from a supply (not shown). The insulating discs 20—20 are fed from a pair of hoppers 22—22 positioned above the apparatus, through a pair of articulated feed chutes 23—23, and the apparatus serves to radially slit the discs and apply them uniformly on the central conductor in such a manner that alternate discs are arranged with their slits diametrically opposite one another, as shown in Fig. 11.

15 The central conductor 21 with the discs assembled thereon is advanced through a forming die indicated in general at 24, which serves to form a metallic strip 25 made of copper, or the like, into a tubular outer conductor 26 around the insulating discs 20—20. The conductor, insulating discs and tubular conductor comprise the cable assemblage being advanced at a predetermined rate of speed by a capstan 27 and taken up by suitable means (not shown). A detailed description of the die 24 and the takeup means will not be given, since a further description thereof is not necessary for a complete understanding of the invention:

20 Referring now to Figs. 2 and 3 of the drawings, it will be noted that the disc-applying apparatus comprises a base member 30 having a pair of spaced vertical supports 31—31 between which a pair of parallel horizontal guide bars 32—32 are rigidly mounted. A slide 33 is slidably mounted on the guide bars 32—32 by means of a pair of horizontal bores 34—34 provided therein. The slide 33 is provided with a bore 35 near each corner thereof, each bore having a self-lubricating bushing 36 rigidly fixed therein. Each of the bushings 36—36 has slidably positioned therein a post 37 having the upper ends thereof secured to a boss 40 provided on the underside of a platen 41. The lower ends of the posts 37—37 project through the slide 33 and have springs 42—42 positioned thereover and maintained thereon by means of collars 43—43 pinned on the lower ends of the posts. This arrangement permits vertical movement of the platen 41 with respect to the slide 33 against the action of the springs 42—42.

25 45 A left-hand disc carrier 45 is positioned on the top side of the platen 41 and is rigidly secured to a shaft 46 rotatably mounted in vertically aligned bores 47 and 48 (Fig. 2) provided in the platen 41 and a supporting plate 50, respectively. The plate 50 is secured to the underside of the platen 41 by a plurality of bolts 51—51 and is spaced therefrom by a plurality of tubular spacers 52—52 positioned over the bolts 51—51. A pinion 53 is keyed to that portion of the shaft 46 positioned between the platen 41 and the plate 50 and engages a gear 54 keyed to a shaft 55 rotatably mounted in vertically aligned bores 56 and 57 provided in the platen 41 and the plate 50, respectively. The shaft 55 is provided with a shoulder 58 which, together with a hub 60 provided on the gear 54, serves to maintain the gear 54 in horizontal alignment with the pinion 53.

30 35 The lower end 61 of the shaft 55 which is positioned in the bore 57 projects below the plate 50 and is provided with a vertical slot 62 to receive one end of a torsion spring 63. The other end of the torsion spring 63 is secured to a housing 64 rigidly fixed to the underside of the plate 50 by a plurality of screws 65—65. The torsion

spring 63 serves to apply sufficient torque on the shaft 55 in a counterclockwise direction to maintain a gear actuating arm 66 keyed on the shaft 55 against a stop pin 67 secured to the platen 41 and projecting therebelow.

A right hand disc carrier 70 is positioned on the top of the platen 41 a predetermined distance to the right of the left hand disc carrier 45 and on the opposite side of the advancing conductor 21. The disc carrier 70 is secured to a shaft 71 rotatably mounted in the platen 41 and the plate 50 in substantially the same manner as is the shaft 46, and also has a pinion 72 secured thereon in engagement with the gear 54. The disc carriers 45 and 70 are maintained in the positions shown in Fig. 3 by means of the torsion spring 63 which maintains the arm 66 against the pin 67. Since the discs 20-20 must be uniformly spaced on the conductor 21 by the disc-applying apparatus, the disc carriers 45 and 70 are spaced on the platen 41 so that they will simultaneously assemble two insulating discs 20-20 on the conductor 21 and leave a space therebetween equal to the spacing between four discs or, in other words, sufficient space is provided therebetween for the equal spacing of two more discs.

An oscillatory, backing-up member 73 is positioned on the top of the platen 41 adjacent to the left hand disc carrier 45 and on the opposite side of the advancing conductor 21 (Fig. 3). The member 73 is secured to a shaft 74 rotatably mounted in the platen 41 and the plate 50 in substantially the same manner as is the disc carrier shaft 46, and also has a pinion 75 secured thereon which engages the gear 54. A similar oscillatory backing-up member 76 is positioned on the platen 41 adjacent to the right hand disc carrier 70 and on opposite side of the conductor 21. The member 76 is secured to a shaft 77 rotatably mounted in the platen and plate in substantially the same manner as is the shaft 71, and has a pinion 78 secured thereon which engages the gear 54. The backing-up members 73 and 76 are maintained in their positions shown in Fig. 3 in the same manner as that described for the disc carriers 45 and 70. Since the gear 54 is in engagement with the pinions 53, 72, 75 and 78, any movement of the arm 66 in a clockwise direction away from the stop 67 serves to simultaneously turn the pinions and their respective disc carriers and backing-up members in a counterclockwise direction.

Since the disc carriers 45 and 70 are identical in construction and operation, but merely reversed as to their position with respect to the conductor 21, the following description applies equally to both of them although directed specifically to the disc carrier 45. Referring to Fig. 8, it will be noted that the disc carrier 45 is provided with a radial disc engaging shoulder 80 formed by an arcuate portion 81 having an arcuate groove 82 cut in the periphery thereof and communicating with the shoulder 80. The radial shoulder 80 is provided on the disc carriers 45 and 70 to engage annular, insulating discs 20-20 positioned thereagainst by means presently to be described, and to carry said discs through an arcuate path so as to assemble the disc on the conductor 21 when said disc carriers are turned in one direction by actuation of the arm 66. The groove 82 cut in the periphery of the arcuate portion 81 permits the shoulders 80-80 of the disc carriers to be positioned transversely of the conductor 21 (Fig. 5).

The backing-up members 73 and 76 have configurations identical with that of the disc carrier

45 and are turned in exactly the same manner as the disc carrier 45. The corresponding shoulders 80-80 formed on the backing-up members 73 and 76, which are turned simultaneously with the disc carriers 45 and 70, provide stops against which the discs are directed when the disc carriers are fully actuated by the arm 66.

Knives 83 and 84 are positioned on the top of the platen 41, adjacent to the disc carriers 45 and 70, respectively. Since the knives 83 and 84 are identical in construction, but oppositely disposed, a detailed description will be given of only the knife 83 positioned adjacent to the carrier 45 (Figs. 2 and 8). The knife 83 is provided with a body portion 85 having a pair of bores 86-86 therethrough for receiving bolts 87-87 which secures the knife to the platen 41. A hardened steel knife blade 90 is secured to a tapered face 91 provided in one end of the body portion 85, which blade gradually tapers from a very sharp cutting edge 92 to a substantially thicker back edge 93. The body portion 85 of the knife 83 is provided with a vertical shoulder 94 which is at a right angle to the cutting edge 92 and extends therefrom to a point substantially in line with the shoulder 80 provided on the adjacent disc carrier.

Each of the knives 83 and 84 is positioned on the platen 41 so that their respective cutting edges 92-92 are adjacent to the disc engaging shoulders 80-80 provided on their respective disc carriers. The cutting edge 92 of the blade 90 is spaced from the shoulder 80 so as to permit an insulating disc 20 to be positioned therebetween when the disc carriers are in their normal disc receiving positions, and is horizontally aligned with the arcuate groove 82 provided in the disc carriers. The groove 82 permits the disc engaging shoulder 81 to be moved past the knife blade 90 from the cutting edge thereof to a transverse position with respect to the conductor 21, whereby a disc engaged thereby is thrust against the cutting edge 92 which cuts a radial line-like slit in the disc from the central aperture to its periphery. As the disc 20 is carried over the knife blade 90 by the disc carrier, the slit is gradually spread apart until it reaches the back edge 93, at which point the slit is now spread sufficiently so that the carrier may assemble it on the adjacent conductor 21 with a wiping motion. The end of the knife blade 90 is shaped to conform with the arcuate path travelled by discs over the blade, for the purpose of maintaining the slit open until the central aperture of the disc is practically in a position to be engaged by the conductor 21. By holding the slit open as long as possible, the amount of contact between the conductor and the sides of the slit is minimized and prevents the ends of the slit previously cut in the disc from being thrust against the conductor and from being damaged or deformed thereby.

Also positioned on the top of the platen 41 are the bottom sections 95-95 of the articulated feed chutes 23-23, each of which is provided with a T-shaped slot 96 which directs the discs 20-20 from the hoppers 22-22 to the disc engaging shoulders 80-80 of the disc carriers 45 and 70. Each bottom section 95 has its T-shaped slot 96 directly aligned with the shoulder 80 of its respective disc carrier (Fig. 8) and is rigidly secured to a spacer block 97 by an L-shaped support 98 so that a sliding fit is obtained between the bottom 99 of each chute 95 and the arcuate portion 81 of the respective disc carriers 45 and 70 (Fig. 4). The arcuate portion 81 provided on

the disc carriers serves to hold the discs 20-20 in the chutes 95-95 as the carriers are turned in a counterclockwise direction by actuation of the gear arm 66. The shoulder 94 provided on the body of each knife 83 and 84 (Fig. 8) serves to maintain a disc in proper position against the shoulder 80 of its respective disc carrier after the disc has dropped in place between the shoulder and the cutting edge 92 of the blade 90. The tapered face 91, which connects with the shoulder 85, serves to guide the disc 11 across the knife blade 90 when the disc carrier 45 is turned in a counterclockwise direction by a clockwise movement of the arm 66.

A rectangular plate 100 is mounted directly under the plate 50 and is spaced therefrom by means of springs 101-101 surrounding posts 102-102 threadedly secured in vertical positions at the corners of the plate 100. The upper end of each post 102 is slidably positioned in a vertically aligned bore 103 provided in the plate 50, and has a pair of nuts 104-104 threadedly mounted thereon for the purpose of adjusting the spacing between the plate 50 and the plate 100 against the action of the springs 101-101 (Figs. 4 and 6). The plate 100 is provided with a central boss 105 so as to provide a substantially thick cross section thereat for a central bore 106 and a counterbore 107. The counterbore 107 is provided to receive a conventional thrust bearing 110 positioned on an upper end 111 and engaged by a shoulder 112 formed on a movable cam follower 113. That portion of the upper end 111 not engaged by the bearing 110 is journaled in the bore 106 of the plate 100. A substantial portion of the lower end of the cam follower 113 is slidably mounted in a self-lubricating bushing 115 secured in a vertically aligned bore 116 provided in the slide 33. The extreme lower end of the cam follower 113 is slotted to form a pair of spaced ears 117-117 between which a roller 118 is rotatably mounted by means of a pin 119 (Figs. 2 and 4).

The roller 118 is resiliently maintained by the springs 42-42 against the periphery of a cam 125 which cam is keyed to a shaft 126 rotatably mounted in a pair of outboard bearings 127-127 (Fig. 2) secured to the base 30 and in a bearing 128 provided in the right hand support 31. A barrel cam 130 (Figs. 2 and 6) also is keyed to the shaft 126 and has provided around its periphery an irregularly shaped cam track 131, which begins at a left hand reversing point 132, proceeds spirally in a counterclockwise direction around substantially two-thirds of the periphery of the cam 130 to a right hand reversing point 133, and then returns to the left hand reversing point 132. A cam follower 135 is rotatably mounted on the end of a flanged stud 136 rigidly secured on the underside of the right hand end of the slide 33 (Figs. 2 and 6), and rides in the cam track 131. The right hand end of the shaft 126 extends through the support 21 and has a gear 137 positioned thereon, which engages a gear 138 secured on the output shaft of a suitable gear reducer 140. The gear reducer 140 has a sprocket 141 secured to its input shaft which is engaged by a roller chain 142 connected to suitable driving means (not shown).

When power is supplied to the input shaft of the gear reducer 140, it serves to drive the shaft 126 in a counterclockwise direction as viewed in Fig. 4, whereby the track 131 of the barrel cam 130 acting against the follower 135 positioned thereon drives the slide 33, the platen 41

and the associated parts to the right until the follower 135 reaches the right hand reversing point 133. When the reversing point 133 is passed, cam track 131 and the follower 135 move the slide 33 and parts carried thereby to the left until the reversing point 132 is engaged by the follower. The barrel cam 130 is designed so that one complete revolution thereof will cause one complete reciprocation of the slide 33 and is driven at such a rate of speed by the reducer 140 that it will drive the slide from left to right at the same rate of speed as that travelled by the conductor 21 being advanced by the capstan 27 (Fig. 1) and from right to left at approximately three times the rate of speed at which it travelled from left to right.

A spring biased latch 160 is pivotally mounted on a stud 161 threadedly mounted on a block 162 secured to a post 163 slidably positioned in an elongated bore 164 provided in a boss 165 secured on the base 30. The block 162 is provided with a longitudinal groove 166 in the inner face thereof which is slidably engaged by the forward end of the plate 50, whereby the latch 160 is maintained in horizontal alignment at all times with the gear actuating arm 66. A spring 168 is positioned under the head of the stud 161 and serves to maintain a leg 170 of the latch 160 against a stop pin 171 and a leg 172 thereof in the path of travel of the arm 66. When the barrel cam 130 causes the slide 33 to carry the arm 66, together with its associated parts to the right, a tapered end 173 provided on the arm 66 engages the leg 172 of the latch 160 which, being secured to the non-reciprocating block 162, urges the arm 66 in a clockwise direction until it reaches the position shown in Fig. 5.

As the arm 66 is carried past the latch 160 by the movement of the slide 33, a spring pressed tripping lever 174 is being carried by the platen 41 toward the leg 170 of the latch 160. The tripping lever 174 is pivotally mounted on a pin 175 threadedly secured to an arm 176 secured on the top of the platen 41 (Fig. 4). The lever 174 has an oblique end 177 provided thereon which is maintained against a flange 178 provided on the end of the arm 176 by a compression spring 179 positioned between the flange 178 and the end of the lever 174 (Figs. 2, 5 and 7). The lever 174, when moving to the right with the slide 33 and the platen 41, engages the leg 170 of the latch 160 and rotates the latch about the stud 161 against the action of the return spring 168, whereby the leg 172 is disengaged from the end 173 of the arm 66. Fig. 7 shows the position of the latch 160 with respect to the lever 174 and the gear actuating arm 66 at the end of the right hand stroke of the slide 33.

The cam 125 keyed to the shaft 126 is also being driven thereby in a counterclockwise direction, as viewed in Fig. 4 and is designed to raise and lower the platen 41 in timed relation with the reciprocation of the slide 33 by the barrel cam 130. The cam 125 is provided with a short arcuate portion 180, an ascending portion 181, a longer arcuate portion 182 and a descending portion 183. The cam 125 is so positioned on the shaft 126 that when the follower 135 engages the left hand reversing point 132 of the cam track 131, the cam follower roller 118 is positioned at the beginning of the arcuate portion 182 (Fig. 4). The arcuate portion 182 of the cam 125 and the descending portion 183 thereof correspond to that portion of the track 131 of the cam 130 which drives the slide 33 to the right. The arcuate portion 180 of

the cam 125 and the ascending portion 181 thereof correspond to that portion of the track 131 which drives the slide 33 to the left.

The arcuate portion 180 of the cam 125 controls the lowermost position of the platen 41, since the springs 42-42 constantly urge the platen 41 downwardly and cause the cam follower roller 118 to engage the periphery of the cam 125. The uppermost position of the platen is controlled by the arcuate portion 182 and by a pair of stop posts 185-185 (Figs. 2 and 4) threadedly secured on the top side of the slide 33 and at opposite ends thereof. Each of the posts 185-185 slidably engage a vertically aligned bore 186 provided in the platen 41 and has a pair of stop nuts 187-187 threadedly mounted on the upper end which projects above the top of the platen. The stop nuts 187-187 are so positioned on the posts 185-185 that when the platen is raised to its uppermost position, the arcuate portion 182 of the cam 125, it abuts the nuts 187-187. When the platen 41 is maintained in this position, the peripheral grooves 82-82 provided in the disc carriers 45 and 70 and their respective backing-up cams 73 and 76 are centrally aligned with the conductor 21 being longitudinally advanced above the platen.

When the arcuate portion 182 of the cam 125 engages the roller 118 mounted on the end of the cam follower 113, it urges the follower 113 and the plate 100 upwardly, which upward movement is transferred to the plate 50 and the platen 41 through the springs 102-102. The compression springs 102-102 are substantially stronger than the compression springs 42-42 and therefore when the arcuate portion 182 urges the plate 100 upwardly, the springs 42-42 are compressed while the springs 102-102 remain unaffected and transfer the upward movement to the platen 41. After the platen 41 has been elevated so that the top side thereof abuts the stop nuts 187-187, further upward travel of the platen is prevented, and any additional upward travel of the cam follower and plate caused by the arcuate portion 182 is now taken up by the stronger compression springs 102-102 provided between the plate 100 and the plate 50.

The springs 42-42 and 102-102 operate in the reverse order when the slide 33 and the parts carried thereby reach the end of the right hand stroke and the roller 118 travels along the descending portion 183 of the cam 125. Now the springs 102-102 urge the plate 100 downwardly until the stop nuts 104-104 engage the upper surface of the stationary plate 50 and thereafter the springs 42-42 urge the platen 41 downwardly and cause the roller 118 to follow the contour of the descending periphery 183 of the cam 125.

A support 190 is rigidly secured on the top of the left hand support 31 and is provided with a pair of spaced ears 191-191 between which a roller 192 is rotatably mounted by means of a pin 193 secured in the ears 191-191. The roller 192 is provided with a V-shaped peripheral groove 194 which engages the central conductor 21 as it is being advanced longitudinally above the platen 41 and coacts with the outer conductor forming die 24 to maintain the conductor 21 in horizontal alignment with the platen and disc carriers. The V-shaped groove 194 of the roller 192 also serves to properly position the advancing conductor 21 between the disc carriers 45 and 70 and to support it against lateral movement when discs are being applied thereby on the central conductor 21.

The centrally perforated, annular discs 20-20

which are to be assembled on the conductor 21 are dumped in sufficient quantities in the hoppers 22-22 from time to time. Since the hoppers 22-22 and their associated feed chutes 23-23 are similar in construction and operation, but merely spaced apart to suit the spacing of the disc carriers on the platen 41, the following description applies to both units, although specifically directed to the left hand unit.

Each hopper 22 is rigidly secured in place above the disc-applying apparatus by a standard 199 and comprises a rectangular housing 200 (Figs. 1 and 12) having sloping bottom sections 201-201 which converge toward the center of the housing 200 and have legs 202-202 formed vertically thereon, so as to leave a longitudinal slot 203 in the extreme bottom of the housing. Secured on the right hand end of the vertical legs 202-202 are a pair of spaced supports 204-204 between which are pivotally mounted brackets 205-205 by means of a pin 206. The brackets 205-205 join together a fan-shaped disc pickup arm 207 and a top feed chute section 208 so that the bottom of a longitudinal groove 210 provided in the upper edge of the arm 207 (Figs. 1 and 12) is aligned with the T-shaped slot 96 provided in the chute section 208. A sliding fit is provided between the arm 207 and the wall of the slot 203 formed by the legs 202-202 so that discs will not fall out of the hopper between the arm 207 and the tapered bottom of the housing 200.

The chute section 208 is the top section of the articulated feed chute 23 and is joined by means of a hinge 211 to one end of an intermediate chute section 212 also having a T-shaped slot 96 provided therein. The other end of the chute section 212 is hingedly connected at 213 to the upper end of the chute section 95 secured on the platen 41 directly over the disc carrier 45.

The hinged joints 211 and 213 between the chute sections 95, 208 and 212 permit the platen 41 to be reciprocated and still receive discs from the stationary hopper 22. The reciprocation of the platen 41 together with the raising and lowering movement thereof combine to raise and lower the disc pickup arm 207 within the housing 200. As the arm 207 moves upwardly through a mass of discs placed in the hopper 22, a plurality of discs fall into the groove 210 and roll along the bottom thereof into the T-shaped slot 96 provided in the chute section 207 and thence into the T-shaped slots 96-96 provided in the chute sections 212 and 95, respectively.

The hinged joints 211 and 213 of the articulated chute 23 are constructed substantially as shown in Fig. 13. Each joint has a flat spring 216 secured in the T-slot so as to close the T-slots at the joint. The flat spring 216 is positioned in an undercut portion 217 provided in the outer edge of the T-slot of each chute section adjacent to a hinged joint and has only one end thereof secured at each hinged joint by a pair of rivets 218-218, so that the other end thereof is free to slide in the undercut portion as the movement of the corresponding joint requires.

Operation

The above-described apparatus operates as follows:

It will be assumed that the slide 33, the platen 41 and the parts carried thereby are positioned at the beginning of a disc-applying stroke, as shown in Fig. 2, in which case the follower 135 is positioned in the cam track 131 at the left hand reversing point 132, and the beginning of the arcuate portion 182 of the cam 125 engages the cam

follower roller 118 so that the platen 41 is elevated to its uppermost position against the stop nuts 187—187. The barrel cam 130 and the cam 125 are being rotated in a counterclockwise direction, as seen in Fig. 4, by suitable power supply (not shown) through the gear reducer 140 so that the rate of rotation of the barrel cam is such that the cam track 131 will drive the slide 33 to the right at the same rate of speed as that at which the capstan 27 is advancing the conductor 21 to the right above the platen 41. As the barrel cam 130 drives the slide 33 to the right in timed relation with the advancing conductor 21, the tapered end 173 of the gear actuating arm 66 engages the leg 172 of the spring biased latch 160 mounted on the non-reciprocating support 162 and the arm 66 is moved by the leg 172 in a clockwise direction against the action of the torsion spring 63 secured on the end of the gear shaft 55.

This movement of the arm 66 turns the gear 54 in a clockwise direction, which in turn simultaneously rotates the pinions 53, 72, 75 and 78 secured to the shafts 46, 71, 74 and 77, respectively, on which are mounted the disc carriers 45 and 70 and the backing-up members 73 and 76, respectively. When the disc carriers 45 and 70 are so rotated in one direction, their respective shoulders 80—80 engage and carry with it one of the centrally perforated circular discs 20—20 fed from the hoppers 22—22 through the articulated feed chutes 23—23. Each disc carrier thrusts a disc engaged thereby against the cutting edge 92 of its companion knife blade 90, whereby a radial, line-like slit is cut in the disc. As the slide 33 continues to travel past the latch 160 and further actuates the arm 66, the discs are carried over the knife blade 90 by the disc carriers, the slit in each disc is held open by the knife blade and spread sufficiently by the back edge 93 thereof so that the disc carriers may slide the discs on the conductor 21 by means of the slits with a wiping motion. Each disc is carried by the carrier until it is placed in a transverse position on the conductor, in which position it abuts the shoulder 80 provided on its adjacent backing-up member which is rotated simultaneously with its respective disc carrier.

When the slide 33 has completed a substantial portion of its right hand stroke, as shown in Fig. 5, the arm 66 has been fully actuated to cause the disc carriers to oscillate 90° and to apply the insulating discs 20—20 engaged thereby transversely on the central conductor 21. Also the tripping lever 174 carried by the arm 175 secured on the moving platen 41 has engaged the leg 170 of the latch 160 and rotated it about the stud 161 to a point where it is practically disengaged from the tapered end 173 of the arm 66. A very slight further movement of the arm 174 to the right rotates the latch 160 to a position where the leg 172 is completely withdrawn from the path of the end 173 of the arm 66, whereupon the arm 66 is instantly returned to its normal position against the pin 71 by the action of the torsion spring 63. The torsion spring 63 rotates the gear 54 in a counterclockwise direction and thereby turns the disc carriers 45 and 70, together with their backing-up members 73 and 76, back to their normal disc receiving positions leaving the discs previously carried thereby positioned on the conductor 21.

A small portion of the remainder of the right hand or disc-applying stroke of the slide 33 is allotted for the purpose of allowing the torsion

spring 63 sufficient time to completely return the disc carriers and backing-up cams to their normal disc receiving positions. By the time the disc carriers 45 and 70 have returned to their respective disc receiving positions (Fig. 3), the cam 125 has been rotated to the extent that the roller 118 of the cam follower 113 has travelled completely across the arcuate portion 182 and now engages the descending periphery 183 of the cam. As the slide 33 proceeds to the end of the stroke, the cam 125 is further rotated and the roller 118 reaches the beginning of the arcuate portion 181 whereupon the platen 41 and disc carriers 45 and 70 are fully lowered to a point where the tops of the disc carriers are substantially below the periphery of the discs previously assembled on the conductor. The slide 33 had then reached the end of its right hand stroke because the cam follower 135 reached the right hand reversing point 133 (Fig. 6).

During that portion of the revolution of the barrel cam 130 which drives the slide 33 from left to right, the roller 118 of the cam follower 113 will assume a diagonal position with respect to the longitudinal axis of the cam 125 and the slide 33. This is due to the fact that the cam 125 is rotating about its axis while the slide 33, together with the cam follower 113, is moving along its longitudinal axis either from left to right or vice versa, so that the resultant effect of the rotary movement and the longitudinal movement causes the roller 118 to assume a diagonal position with respect to the longitudinal axis of the cam 125. The thrust bearing 110 provided in the plate 100 permits the cam follower 113 and its roller 118 to swivel to the proper angle whereby a minimum amount of drag of the roller 118 across the periphery of the cam 125 is assured.

The slide 33 and the platen 41 are now in position to be returned to the left to their normal starting position without interfering with the discs just assembled on the conductor during the right hand stroke of the slide. Further rotation of the cam 130 causes the cam follower 135 to move toward the reversing point 132, whereby the slide 33 is driven to the left. When the slide 33 has completed a substantial portion of its left hand stroke, the cam 125 has rotated so as to bring the ascending periphery 182 into engagement with the roller 118, whereby it starts to elevate the platen 41. When the cam follower 135 reaches the left hand reversing point 132, the slide 33 has fully completed its left hand stroke, at which time the cam 125 has rotated so as to bring the beginning of the arcuate portion 181 into engagement with the cam follower roller 118 which again elevates the platen 41 and the disc carriers to their uppermost positions. During the left hand stroke of the slide 33, the arm 66 carried by the slide engages the leg 172 of the latch 160 and urges it in a counterclockwise direction against the action of the return spring 168 so that the arm 66 may pass by the latch 160 and again assume its starting position to the left of the latch as shown in Fig. 3.

The very instant that the slide 33 begins another right hand stroke in timed relation with the conductor 21, it again establishes two spaced points thereon at which discs are to be assembled by the disc carriers. The discs are assembled on the conductor 21 by subsequent right hand strokes of the slide 33 in staggered relationship with respect to the discs assembled thereon by the previous right hand stroke. This is due to

the fact that the portion of the cam track 131 of the barrel cam 130 which drives the slide 33 to the left is approximately only one-third as long as that portion of the track 131 which drives the slide to the right. As a result the slide 33 is driven to the left at a rate of speed substantially three times greater than that at which it travels on its right hand stroke. In this way the disc assembled on the conductor 21 by the left hand carrier 45 during the previous right hand stroke of the slide travels with the conductor to the right only one-third the distance that is travelled by the slide and disc carriers on the left hand stroke. Consequently, the right hand carrier 70 establishes its new disc assembling position with respect to the conductor 21 at the required distance to the right of the disc previously applied by the left hand carrier 45, so that discs 20—20 will be uniformly spaced on the conductor 21 and according to a predetermined pattern.

To illustrate clearly how the above-described apparatus assembles discs in uniform spaced relation on a continuously moving conductor, let it be assumed that the conductor 21 is moving constantly to the right, as seen in Fig. 1, at a rate of 16 feet per minute, that it is desired to space the discs $1\frac{1}{8}$ " apart on the conductor, that the disc carriers 45 and 70 are spaced $3\frac{3}{8}$ " apart on the platen or the cumulative space of three discs, and that a disc-applying stroke of $1\frac{1}{4}$ " of the slide 33 is required to completely actuate and release the disc carriers and lower the platen. Referring to Fig. 16, the legend "Stroke 1" indicates that the two discs adjacent to the ends of the bracket were assembled on the conductor by the first disc-applying or right hand stroke of the apparatus $3\frac{3}{8}$ " apart. The disc assembled thereon by the left hand carrier 45 is designated "L1" and the disc assembled by the right carrier 70 is designated "R1."

Since it is required to space the discs $1\frac{1}{8}$ " apart, the next position to be assumed by the right hand carrier 70 is $2\frac{1}{4}$ " to the left of disc R1. The left hand stroke of the slide is such that it will absorb $1\frac{1}{4}$ " of this distance while the conductor moves to the right $\frac{1}{2}$ ". Since there is no relative movement between the conductor and the disc carriers during the disc-applying strokes, the apparatus will assemble two more discs R2 and L2 on the conductor at the positions established at the termination of the previous left hand stroke as stated above, which positions are indicated by the ends of the bracket marked "Stroke 2." Upon the completion of "Stroke 3," the discs designated "R3" and "L3" will have been applied, and the four discs R2, L1, R3 and L2 are uniformly spaced on the conductor $1\frac{1}{8}$ " apart, as shown in Fig. 16. Subsequent to "Stroke 3" the apparatus will assemble discs on the conductor in the desired uniform pattern.

It will be noted that blank spaces will be left between the first two discs and between the last two discs of the coaxial unit. Obviously, these ends comprise only a fraction of the total length of a coaxial cable unit, which may be about 1500 feet, or more, long. If desired, the missing discs may be applied in these vacant spaces by a manually operated disc-applying device of the type disclosed in my copending application, Serial No. 653,884, filed March 12, 1946. Or the ends of the coaxial unit may be cut off.

The disc assembling apparatus outlined hereinabove facilitates the use of the relatively soft

plastic material polyethylene in the manufacture of coaxial cables. Since the apparatus disclosed herein merely slits the insulating discs, no material is removed therefrom and such discs when positioned on the conductor adhere thereto with a substantially greater force than it is possible to obtain by slotted discs made from such a soft plastic material. In addition to this feature, discs which are merely slit and then applied to the conductor form a substantially solid ring around the conductor because the inherent elasticity of the material tends to close the slits made in the discs.

While the insulating discs 20—20 preferably are made of polyethylene, the methods and apparatus embodying the invention may be used equally well to apply discs made of other relatively soft insulating materials to central conductors. For example, the insulating discs may be made of cellulose acetate or mixtures of cellulose acetate and cellulose butyrate, or may be fabricated from relatively soft products obtained by polymerizing vinyl compounds, such as are obtained by polymerizing vinyl chloride and vinyl acetate or mixtures thereof.

What is claimed is:

1. Apparatus for assembling insulating discs on a continuously moving conductor, which comprises means for continuously advancing a conductor along a predetermined path, a reciprocable member arranged to move parallel to the moving conductor, a plurality of disc carriers spacedly positioned on the reciprocable member in spaced relation with respect to each other and the moving conductor, said disc carriers being rotatably mounted on the member to have oscillatory movement with respect to the longitudinal axis of the moving conductor, means provided on the member for feeding centrally perforated insulating discs in position to be engaged by the disc carriers, each disc carrier being arranged to carry a single disc at a time, means positioned adjacent to each disc carrier for cutting a radial slit from the center perforation to the periphery of the disc carried thereby, means for reciprocating the reciprocable member so that it travels in unison with the conductor and returns at a substantially faster rate of travel in a direction opposite to that of the advancing conductor, and means for simultaneously actuating the disc carriers through a predetermined portion of one revolution as the reciprocable member is moved in the same direction as the advancing conductor so that a disc engaged by each carrier is carried past the radial slitting means and assembled on the conductor with an arcuate wiping motion.

2. Apparatus for assembling insulating discs on a continuously moving conductor, which comprises means for advancing a continuous, filamentary conductor along a predetermined path, a reciprocable member positioned parallel to and beneath the moving conductor, a pair of disc carriers spacedly positioned on the reciprocable member longitudinally of and at opposite sides of the moving conductor, means associated with the reciprocable member for positioning centrally perforated insulating discs in position to be engaged by the disc carriers, means adjacent to each disc carrier for cutting a radial slit in the disc carried thereby, said disc carriers being arranged on said member to have an oscillatory movement with respect to the longitudinal axis of the moving conductor, means for reciprocating the reciprocable member, means for simultaneously turning the disc carriers in one direction,

through a predetermined portion of one revolution when the reciprocable member is moving in the same direction as the conductor to cause each disc carrier to pick up an insulating disc, carry it by the cutting means and position it on the moving conductor with an arcuate wiping motion, and means associated with the reciprocable member for positioning the disc carriers in horizontal alignment with the advancing conductor when said reciprocable member is moving in the same direction therewith and for retracting the disc carriers after they have assembled discs on the conductor, whereby the reciprocable member may be returned to its starting position without any members striking the discs applied to the conductor.

3. Apparatus for assembling insulating discs on a continuously moving conductor, which comprises means for advancing a filamentary conductor along a predetermined path, a reciprocable member arranged to operate parallel to and beneath the moving conductor, a pair of rotatable disc carriers spacedly positioned a predetermined distance apart on the reciprocable member so that one carrier is positioned on each side of the conductor, a rotatable backing-up member positioned on the reciprocable member directly opposite each disc carrier, means associated with the reciprocable member for feeding centrally perforated discs in position to be engaged by the disc carriers, means positioned adjacent to each disc carrier for cutting a radial slit in the disc carried thereby, means for reciprocating the reciprocable member, means for simultaneously turning the disc carriers and the backing-up members, non-reciprocating means associated with the reciprocable member for actuating the means for turning the disc carriers and backing-up members in one direction a predetermined portion of one revolution when the reciprocable member is moving in the same direction as the advancing conductor, said disc carriers and backing-up members being arranged on said member to have an oscillating movement with respect to the longitudinal axis of the moving conductor so that when the disc carriers are actuated they apply the disc carried thereby on the conductor with an arcuate wiping motion, and resilient means provided on the reciprocable member for returning the disc carriers and backing-up members to their normal positions on the reciprocable member after they have been turned to apply and back-up respectively, a disc on the conductor.

4. Apparatus for assembling insulating discs on a continuously moving conductor, which comprises means for advancing a filamentary conductor along a predetermined path, a reciprocable member positioned parallel to and beneath the moving conductor, a pair of rotatable disc carriers arranged on said reciprocable member in a predetermined spaced relation longitudinally of and on opposite sides of the moving conductor, said disc carriers being arranged on the reciprocable member to have an oscillatory movement with respect to the longitudinal axis of the advancing conductor, means associated with said member for successively feeding centrally perforated insulating discs in position to be engaged by the disc carriers, resilient means for maintaining the disc carriers in their normal disc receiving position, means for reciprocating the reciprocable member so that it travels in unison with the conductor and substantially faster in a direction opposite to the direction of

travel of the conductor, means for cutting a radial slit in each disc as it is carried by its respective disc carrier, a cam oriented with the reciprocating means for aligning the disc carriers with the advancing conductor as the reciprocable member is moved in the same direction as the conductor and for retracting the disc carriers before the reciprocable member is moved in an opposite direction to that of the moving conductor, and means for simultaneously turning the disc carriers in one direction through a predetermined portion of one revolution against the action of said resilient means when the member is moving in unison with the conductor to cause the carriers to pick up discs, carry them past the radial slitting means and simultaneously assemble the discs on the conductor with an arcuate wiping motion, whereby when said disc carriers having completely assembled discs on the conductor said resilient means serves to turn the disc carriers in the opposite direction to their disc receiving positions.

5. Apparatus for assembling insulating discs on a continuously moving filamentary conductor, which comprises a reciprocably mounted slide positioned parallel to and beneath a moving conductor, a vertically movable platen resiliently mounted on said slide and reciprocable therewith, means for reciprocating the slide, a pair of rotatable disc carriers spacedly positioned on the platen so as to be disposed on opposite sides of the moving conductor, means for imparting vertical movement to the platen so as to align the disc carriers with the moving conductor as the slide is moved in unison with the conductor and for retracting the platen before the slide is moved in a direction opposite to that of the conductor, said disc carriers being arranged on the platen to have an oscillatory movement with respect to the longitudinal axis of the conductor, means provided on the platen for simultaneously turning the disc carriers in one direction, non-reciprocating means for actuating the disc carrier turning means through a predetermined portion of one revolution when the slide is moving in unison with the conductor to cause each carrier to apply a disc engaged thereby on the conductor with an arcuate wiping motion, and means secured to the platen and slidably engaging the non-reciprocating actuating means so as to maintain the said actuating means in horizontal alignment with the disc carrier turning means throughout the reciprocation of the disc carriers.

6. An apparatus for assembling insulating discs on a continuously moving conductor, means for advancing the conductor along a predetermined path of travel, which comprises a reciprocably mounted slide arranged to operate parallel to and beneath the moving conductor, a vertically movable member resiliently mounted on the slide so that normally it is positioned below the moving conductor, means for reciprocating the slide so that it travels in unison with the conductor and returns at a substantially faster rate of speed in a direction opposite to that of the moving conductor, a pair of rotatable disc carriers spacedly mounted on the vertically movable member on the opposite sides of the conductor so as to have an oscillatory movement with respect to the longitudinal axis of the conductor, means associated with the vertically movable member for feeding centrally perforated discs to be engaged by the carriers, said disc carriers arranged to engage a single disc at a time, means positioned adjacent to each disc carrier for radially slitting

discs engaged thereby, means for raising the vertically movable member so as to align the slitting means with the conductor when the slide is moved in the same direction as the moving conductor and for lowering the vertically movable member as the slide is moved in a direction opposite to that of the moving conductor, and means for simultaneously turning the disc carriers through a predetermined portion of one revolution as the reciprocable member is moved in the same direction as the advancing conductor, whereby when the disc carriers are actuated a disc engaged thereby is carried past the slitting means and assembled on the conductor with an arcuate wiping motion, said slitting means serves to hold open the slits cut in the discs thereby so that the discs carried by the applicator may be assembled by the conductor without damaging the disc.

7. An apparatus for assembling insulating discs on a continuously moving conductor, which comprises means for advancing a filamentary conductor along a predetermined path, a reciprocable member positioned parallel to and beneath the moving conductor, a plate resiliently mounted on top of the reciprocable member and normally spaced below the moving conductor, a pair of disc carriers rotatably mounted on the vertically mounted plate so as to be spaced in predetermined relation on opposite sides of the moving conductor, said disc carriers having a single disc engaging shoulder provided thereon and a groove cut in the periphery thereof so as to communicate with said shoulder, means associated with the resiliently mounted plate for feeding centrally perforated discs in a position to be engaged by the shoulder of each disc carrier, a knife positioned on the plate adjacent to each disc carrier for cutting a radial slit in the disc carried thereby, means for raising the resiliently mounted plate so as to position the back of said knife blade in horizontal alignment with the movable conductor as the slide is moved in unison with the conductor, means for reciprocating the reciprocable member so that the disc carriers move in unison with the conductor and at a substantially faster rate of speed than that of the conductor when moved in a direction opposite to the moving conductor, means for simultaneously turning the disc carriers in one direction through a predetermined portion of one revolution as the reciprocable member is moved in the same direction as the advancing conductor, whereby the discs engaged by the radial shoulder of each carrier is carried thereby past the radial slitting means and assembled on the conductor with an arcuate wiping motion in predetermined spaced relation with respect to each other.

8. An apparatus for assembling insulated discs on a continuously moving conductor, which comprises means for advancing a filamentary conductor along a predetermined path, a reciprocably mounted slide positioned parallel to and beneath the moving conductor, a vertically movable member resiliently mounted on the slide so as to be positioned normally below the moving conductor, means for reciprocating the slide so that the slide moves in unison with the conductor and at a substantially faster rate of travel when the slide is moved in a direction opposite to that of the moving conductor, a pair of disc carriers rotatably mounted on the vertically movable member so as to be disposed in predetermined spaced relation on opposite sides of the moving conductor, means associated with the vertically

movable member for feeding centrally perforated discs in position engaged by the disc carriers, a knife positioned on the vertically movable member adjacent to each disc carrier with its cutting edge facing the disc engaging shoulder of its carrier for cutting radial slits in the disc carried thereby, means for simultaneously turning the disc carriers in one direction through a predetermined portion of one revolution as the reciprocable member is moved in unison with the conductor, and means for elevating the resiliently mounted plate so as to align the back of the cutting knife with the moving conductor so that when the disc carriers are turned the discs engaged thereby are carried across the knife and then applied on the conductor adjacent to the back edge of the knife, said elevating means being arranged to retract the resiliently mounted plate at the end of the disc applying stroke of the resiliently mounted slide so that the slide may be moving in a direction opposite to that of the moving conductor, whereby successive operation of the slide serves to assemble the insulating discs on the moving conductor in uniform spaced relation.

25 9. An apparatus for assembling insulating discs on a continuously moving conductor, which comprises means for advancing a filamentary conductor along a predetermined path of travel, a reciprocably mounted slide arranged to operate parallel to and beneath the moving conductor, said slide having a cam follower secured to one end thereof, a barrel cam positioned beneath the slide and having a track engaged by said cam follower, said barrel cam serving to reciprocate the slide so that it travels in unison with the conductor but is moved at a substantially faster rate of speed when it is moving in a direction opposite to that of the moving conductor, a vertically movable platen resiliently mounted on the slide and spaced beneath the moving conductor, a pair of disc carriers rotatably mounted on the platen so as to be positioned in predetermined spaced relation longitudinally of and at opposite sides of the moving conductor, means for feeding centrally perforated discs in position to be engaged by the disc carriers, a knife blade provided on the platen adjacent to each disc carrier for cutting a radial slit in discs engaged by the disc carriers, a plate spacedly secured to the under side of the platen, gear and pinion means positioned between the platen and said plate for turning the disc carriers, means provided on the platen for turning the gear and pinion means engaged thereby in one direction, a non-reciprocating latch device positioned adjacent to the resiliently mounted platen for actuating the gear turning means so as to oscillate the disc carriers through a predetermined portion of one revolution when the slide is moving in unison with the advancing conductor, means slidably engaged by the plate for maintaining the non-reciprocating latch in a horizontal alignment with the gear actuating means, means carried by the platen for tripping the latch after it has actuated the disc carrier turning means, and means driven in timed relation to the reciprocation of the slide for elevating a platen so as to horizontally align with the knife with the moving conductor when the slide is moving in the same direction as the conductor and for lowering the platen after the discs have been applied on the conductor and before the slide is moved in a direction opposite to that of the moving conductor.
